UNITED STATES PATENT OFFICE.

SELVIYOR A. SWANSON, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

PUMPING MECHANISM FOR AUTOMATIC MUSICAL INSTRUMENTS.

1,264,577.

Specification of Letters Patent. Patented Apr. 30, 1918.

Application filed May 3, 1915. Serial No. 25,395.

To all whom it may concern:

Be it known that I, SELVIYOR A. SWANSON, a citizen of the United States, residing at North Tonawanda, in the county of Niagara and State of New York, have invented new and useful Improvements in Pumping Mechanism for Automatic Musical Instruments, of which the following is a specification.

10 This invention relates to musical instruments which are driven by an electric motor and more particularly to so-called electric player pianos.

It frequently happens that through carelessness or oversight, users or attendants neglect to stop the motor after rewinding or removing the last music roll, in some cases allowing the motor to run all night and incurring a considerable loss of power.

20 One object of my invention is the provision of simple and reliable means for automatically stopping the electric motor after a roll has been played and rewound, thus effectually guarding against such oversight 25 and loss.

In such instruments it is desirable to provide auxiliary pumps or exhaust devices to be used when playing the instrument automatically. Heretofore such auxiliary pumps 30 have been arranged in the rear portion of the piano case where they are difficult of access.

A further object of my invention is an improved arrangement of such auxiliary 35 pumps, with a view of rendering them easily accessible for repairs as well as facilitating their installation in the instrument.

In the accompanying drawings:

Figure 1 is a front elevation, partly in 40 section, of an automatic musical instrument embodying the invention, the front panels or plates of the piano case being removed. Fig. 2 is a horizontal section thereof on line 2—2, Fig. 1. Fig. 3 is an enlarged vertical section 45 of the motor pneumatic which controls the switch of the electric motor. Fig. 4 is an enlarged transverse vertical section on line 4—4, Fig. 2, showing the automatic valve closed.

Similar characters of reference indicate 50 corresponding parts throughout the several views.

1 indicates the customary action wind chest of the instrument, preferably mounted above the key board; 2 the main reservoir; 55 2^a the equalizers and 3 the main suction pumps or feeders which are operated by the customary pedals 4, through suitable connections, not shown in the drawings. As shown, this main reservoir terminates short 60 of the end walls of the frame-case.

5 indicates a valve chamber which, in the example shown, is applied to the front side of the reservoir 2 and connected therewith by a passage 6. This passage is controlled 65 by a sliding or other suitable rewind valve 7, the operating rod 8 of which is connected with the customary key or lever, not shown. The usual main suction chamber of the wind chest 1 is connected with the valve chamber 70 5 by the tube or trunk 9, the wind chest communicating with the reservoir 2 when the rewind valve 7 is opened and cut off therefrom when said valve is closed, in a well known manner.

75 10 indicates the auxiliary suction pumps or feeders and 11 the air chamber or reservoir with which they are connected and on the front side of which they are mounted, as shown. These auxiliary feeders and the 80 companion reservoir are arranged vertically and transversely in one end of the piano case, said reservoir being secured to the adjacent end wall thereof, as shown. 12 indicates a crank shaft arranged transversely in 85 the piano case between the auxiliary feeders and the main reservoir 2 and supported by brackets 13 secured to the ends of the auxiliary reservoir 11, or by other suitable means. The auxiliary pumps are driven 90 from this crank shaft by links 14 while the shaft in turn is driven from an electric or other suitable motor 15 by a belt 16 running around the pulley 17 of the motor shaft and a pulley 18 secured to said crank shaft and 95 preferably arranged in the rear portion of the piano case.

By this arrangement of the auxiliary feed-

UNITED STATES PATENT OFFICE.

SELVIYOR A. SWANSON, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

PUMPING MECHANISM FOR AUTOMATIC MUSICAL INSTRUMENTS.

1,264,577.

Specification of Letters Patent. Patented Apr. 30, 1918.

Application filed May 3, 1915. Serial No. 25,395.

To all whom it may concern:

Be it known that I, SELVIYOR A. SWANSON, a citizen of the United States, residing at North Tonawanda, in the county of Niagara and State of New York, have invented new and useful Improvements in Pumping Mechanism for Automatic Musical Instruments, of which the following is a specification.

10 This invention relates to musical instruments which are driven by an electric motor and more particularly to so-called electric player pianos.

It frequently happens that through carelessness or oversight, users or attendants neglect to stop the motor after rewinding or removing the last music roll, in some cases allowing the motor to run all night and incurring a considerable loss of power.

20 One object of my invention is the provision of simple and reliable means for automatically stopping the electric motor after a roll has been played and rewound, thus effectually guarding against such oversight 25 and loss.

In such instruments it is desirable to provide auxiliary pumps or exhaust devices to be used when playing the instrument automatically. Heretofore such auxiliary pumps 30 have been arranged in the rear portion of the piano case where they are difficult of access.

A further object of my invention is an improved arrangement of such auxiliary 35 pumps, with a view of rendering them easily accessible for repairs as well as facilitating their installation in the instrument.

In the accompanying drawings:

Figure 1 is a front elevation, partly in 40 section, of an automatic musical instrument embodying the invention, the front panels or plates of the piano case being removed. Fig. 2 is a horizontal section thereof on line 2—2, Fig. 1. Fig. 3 is an enlarged vertical section 45 of the motor pneumatic which controls the switch of the electric motor. Fig. 4 is an enlarged transverse vertical section on line 4—4, Fig. 2, showing the automatic valve closed.

Similar characters of reference indicate 50 corresponding parts throughout the several views.

1 indicates the customary action wind chest of the instrument, preferably mounted above the key board; 2 the main reservoir; 55 2^a the equalizers and 3 the main suction pumps or feeders which are operated by the customary pedals 4, through suitable connections, not shown in the drawings. As shown, this main reservoir terminates short 60 of the end walls of the frame-case.

5 indicates a valve chamber which, in the example shown, is applied to the front side of the reservoir 2 and connected therewith by a passage 6. This passage is controlled 65 by a sliding or other suitable rewind valve 7, the operating rod 8 of which is connected with the customary key or lever, not shown. The usual main suction chamber of the wind chest 1 is connected with the valve chamber 70 5 by the tube or trunk 9, the wind chest communicating with the reservoir 2 when the rewind valve 7 is opened and cut off therefrom when said valve is closed, in a well known manner. 75

10 indicates the auxiliary suction pumps or feeders and 11 the air chamber or reservoir with which they are connected and on the front side of which they are mounted, as shown. These auxiliary feeders and the 80 companion reservoir are arranged vertically and transversely in one end of the piano case, said reservoir being secured to the adjacent end wall thereof, as shown. 12 indicates a crank shaft arranged transversely in 85 the piano case between the auxiliary feeders and the main reservoir 2 and supported by brackets 13 secured to the ends of the auxiliary reservoir 11, or by other suitable means. The auxiliary pumps are driven 90 from this crank shaft by links 14 while the shaft in turn is driven from an electric or other suitable motor 15 by a belt 16 running around the pulley 17 of the motor shaft and a pulley 18 secured to said crank shaft and 95 preferably arranged in the rear portion of the piano case.

By this arrangement of the auxiliary feed-

ers and auxiliary reservoir, these parts can be conveniently installed and removed for repairs or other purposes without disturbing the crank shaft 12 and driving wheel 18, 5 or other parts of the instrument.

The auxiliary reservoir is connected by a tube or trunk 19 with a valve chamber 20 which communicates by a port 21 with the main reservoir 2. This port is controlled by 10 a spring-pressed automatic valve 22 of any ordinary construction arranged in said valve chamber and closing toward the main reservoir. By this arrangement, when the main feeders 3 are actuated by the pedals 4 the 15 valve 22 closes automatically, cutting off the auxiliary reservoir and its feeders from the main reservoir, while when the auxiliary feeders are driven by the motor 15, said valve automatically opens, connecting the 20 auxiliary reservoir with the main reservoir and causing it to act upon the wind chest 1 through the main reservoir, thus avoiding the necessity of providing separate equalizers for the auxiliary reservoir.

25 The motor circuit is controlled by a switch of any suitable construction. That shown in the drawings comprises a block 23 of insulating material carrying a pair of opposing contact springs 24 to which the conductors 25 and 26 of said circuit are connected, and a sliding switch plug 27 arranged to enter between said springs. The projecting stem 28 of this switch plug is connected by 30 links 29 and 30 with a hand lever 31 preferably mounted on the tracker box 32. This switch is also adapted to be operated automatically by a suitable pneumatic 33, the movable board of which engages the link 30 in such a manner that when the pneumatic is collapsed, the switch plug 27 is opened 35 and the motor stopped. The action of this pneumatic may be controlled by any suitable or conventional valve mechanism which in turn is controlled by a duct 34 of the tracker 40 board 35. This valve mechanism is shown in Fig. 3, where 36 is a block attached to the pneumatic and containing a suction chamber 37 connected by a tube 38 with the auxiliary reservoir 11. Adjacent to this 45 suction chamber is the valve chamber 39 connected by a port 40 with said suction chamber and by a port 41 with the outer atmosphere. These ports are controlled by the usual valves 42 and 43, the stem of which 50 bears against the pouch or diaphragm 44. The latter covers the usual chamber 45 with which is connected a tube 46 leading to the controlling duct 34. This duct is arranged to be covered by the usual music sheet 47 so 55 long as the sheet passes over or remains in contact with the tracker, but is uncovered when the sheet becomes detached from the hook of the take-up roll 48 during the rewinding of the sheet. When this occurs, the

outer atmosphere entering said controlling duct, presses the diaphragm 44 in the proper direction to open the suction valve 43 and close the flushing valve 42, thereby collapsing the motor pneumatic 33, opening the switch 27 and stopping the motor. As soon 70 as the motor stops, the tension in the suction chamber 37 ceases and the valves 42, 43 return to the position shown in Fig. 3, flushing and expanding said motor pneumatic, the movable board of which assumes the 75 position shown in Fig. 1.

In the use of the instrument, the operator, after attaching the music sheet to the take-up roll, closes the motor-switch by means of the hand lever 31, causing the instrument 80 to play. After the music roll has been played, it is rewound in the usual manner. As soon as it leaves the take-up roll, it uncovers the controlling duct 34, causing the motor pneumatic 33 to open the motor- 85 switch and stopping the motor, as hereinbefore described.

This automatic stop mechanism renders it impossible to completely rewind the music sheet or to remove it without at the same 90 time stopping the motor, thus guarding against waste of current in case the operator should forget or neglect to open the switch of the motor-circuit after playing the last roll. 95

Should the operator close the motor-switch without having previously attached the music sheet to the take-up roll, the atmosphere entering the uncovered controlling duct 34 will actuate the pouch 44, collapsing the 100 motor-pneumatic 33 as before, opening the switch and stopping the motor.

I claim as my invention:

1. In an instrument of the character described, the combination of the piano-case, 105 the key board, a main reservoir arranged below the keyboard and having an equalizer and a pump, said reservoir terminating short of the end walls of the piano-case, 110 peda ls for actuating said pump, an auxiliary reservoir connected with said main reservoir and having a pump, said auxiliary reservoir and its pump being arranged transversely in the piano-case between one of its end walls and the main reservoir, and a motor 115 for said auxiliary pump.

2. In an instrument of the character described, the combination of the piano case, the keyboard, a main air reservoir arranged below the keyboard and having an equalizer 120 and a pump, peda ls for actuating said pump, an auxiliary reservoir connected with said main reservoir and arranged transversely against one of the end walls of the case, an auxiliary pump connected with said reservoir, and a motor for said auxiliary pump. 125

3. In an instrument of the character described, the combination of the piano case,

the keyboard, a main air reservoir arranged below the keyboard and having an equalizer and a pump, pedals for actuating said pump, an auxiliary reservoir connected with said main reservoir and arranged transversely against one of the end walls of the case, an auxiliary pump connected with said reser-

voir, a horizontal crank shaft arranged transversely between said main reservoir and said auxiliary pump, an operative connection between said crank shaft and the auxiliary pump, and a motor for said crank shaft. 10

SELVIYOR A. SWANSON.
